Inventor,

August Wilhelm

United States Patent Office.

AUGUST WILHELM, OF PHILADELPHIA, PENNSYLVANIA.

Design No. 3,686, dated September 28, 1869.

DESIGN FOR A REFLECTOR.

The Schedule referred to in these Letters Patent and making part of the same.

To all whom it may concern:

Be it known that I, AUGUST WILHELM, of the city of Philadelphia, in the county of Philadelphia, and State of Pennsylvania, have invented and designed a new and original Shape for a Light-Reflector, for lamps, street-lanterns, &c., of which the following is a clear and exact description, reference being had to the accompanying drawing, making a part of this description, and to the letters of reference marked thereon.

The drawing represents a vertical longitudinal section, through the centre of the said reflector.

The inside or reflecting-surface of the reflector is formed of the concave curve $b\ a\ b$, and of the convex curves $b\ c$, $b\ c$, as shown in the drawing. The concave curve $b\ a\ b$ is elliptic, the convex curves $b\ c$, $b\ c$ are segments of circles, of which $d\ d$ are the centres.

A reflector, shaped as herein shown and described, can be circular or polygonal.

The black dotted lines and the red lines are merely illustrative of the manner of designing the reflecting-surface of the reflector $e\ b\ a\ b\ e$, and of the resultant direction of the reflected rays of light coming from the focus f , and therefore form no part of the design; but having shown and described the particular shape of the reflector $e\ b\ a\ b\ e$,

What I claim as my invention, and desire to secure by Letters Patent, is—

The design for a reflector, herein shown and described.

AUGUST WILHELM.
